UNITED STATES PATENT OFFICE.

HARRY LOEVEN, OF DOUGLAS, ARIZONA.

COMBINATION CRUSHER AND MILL.

1,409,558.

Specification of Letters Patent. Patented Mar. 14, 1922.

Application filed July 14, 1919. Serial No. 310,547.

To all whom it may concern:

Be it known that I, HARRY LOEVEN, a citizen of the United States, and a resident of Douglas, in the county of Cochise and State 5 of Arizona, have made certain new and useful Improvements in Combination Crushers and Mills, of which the following is a specification.

This invention is an improvement in milling, and one of the principal objects of the 10 invention is to provide a mill having means for crushing, milling, classifying, and screening, either wet or dry, ore or rock in one continuous operation.

15 Another object of the invention is to provide a rotating drum in which the ore or rock is milled and crushed, incorporating spaced bars which form the side walls of the drum and around which is a detachable 20 encircling screen, the ore or rock being milled within the drum and passing between the bars and through the screen into a trough to be conveyed to an amalgamator or any other process of further reduction.

25 Another object is to provide a shaft extending through the drum, rotating in the same direction as and at a greater rate of speed than the drum and carrying means for mauling the ore or rock within the drum 30 until it is fine enough to pass through the spaces between the bars to the screen.

Another object of the invention is to provide a novel means of vibrating the screen.

Still another object is to provide an improved mill which will be extremely simple, durable, efficient in operation, and inexpensive to manufacture and maintain, which will crush, mill, classify and screen ore and rock to any fineness desired and into a wet 40 or dry pulp.

With these and other objects in view, which will become apparent as the description proceeds, the invention resides in the construction, combination and arrangement 45 of the parts hereinafter more fully described and claimed and illustrated in the accompanying drawings, in which like characters of reference indicate like parts throughout the several figures, of which:

50 Figure 1 is a view showing in side elevation one form of combination crusher and mill embodying my invention.

Figure 2 is a view showing in transverse

section the drum embodied in the crusher and mill shown in Figure 1.

55

Figure 3 is a longitudinal section of the drum shown in Figure 2.

Figure 4 is a detailed perspective view of one of the slug discs comprised in the drum shown in the preceding views.

60

In carrying out my invention into use as a quartz mill, I provide a suitable framework indicated generally at 5, associated with which is a drum 6, a hopper 7, through which the ore is dumped into the drum, a 65 slug shaft 8 extending axially through the drum, a trough 9, which receives the milled ore from the drum, an amalgamator 10 into which the milled ore is introduced from the trough, and driving mechanism which will 70 appear in detail hereinafter.

The drum includes end walls 11 and 12, respectively, one of which closes the rear end of the drum, except for an opening to receive the slug shaft 8, and the other of 75 which closes the front end of the drum except for an opening 13 for receiving the discharge end of the hopper 7. Trunnion rings 14 are supported on the end walls of the drums, and present relatively wide surfaces 80 for engaging upon the flanged rollers 15, upon which the drum is supported and rotated. These are two pairs of rollers, each pair being fixed upon a rotatable shaft (not shown). While I have shown means for 85 feeding the drum from one end, a similar means may be installed at the other end also, if desired.

The slug shaft 8, extends axially through the drum, being supported in bearings 16^a 90 and at its forward end is rotated at a great rate of speed by a belt 16 driven from a suitable source of power and running over a pulley 17 carried by the shaft. The drive from the slug shaft goes from a pulley 18 at 95 the rear end of the shaft, through a belt 19 to a relatively large pulley 20 mounted on a counter shaft 21, and from this shaft it goes through gears 22 and 23 to one of the shafts 15^a carrying a pair of the rollers 15 through 100 which the drive to the drum is transmitted. The arrangement of the drive mechanism above described, and the gear reduction produced, is such that the drum is driven in the same direction as the shaft and at a greatly 105 reduced rate of speed. A convenient esti-

mate of the speed of the drum as compared to that of the shaft can be formed from the fact that in practice the drum is driven at about 30 revolutions per minute, while the 5 shaft rotates at about 1000 revolutions per minute.

It will be convenient to note at this point that the amalgamator 10 is mounted on an inclined shaft 24, having a conical pulley 10 at its lower end taking the drive from a belt 25, running over a smaller pulley 26, carried at the rear end of an intermediate shaft 27, which may be driven from a roller shaft at its forward end as at 28 from the 15 other shaft. The amalgamator is driven at a low rate of speed and may be stopped at will by slipping the belt 25 onto an idler pulley 29.

Fixed to the slug shaft 8, at spaced intervals, within the drum, are discs or balance wheels 30, each of which has a plurality of yokes 31 pivoted thereto as at 32. The yokes each support a slug 33, which slug is connected to the yoke by means of a hook or 25 link 34. As the slug shaft rotates the slugs are thrown out by centrifugal force and rotate in paths slightly spaced from the wall of the drum, thus grinding and mauling the ore which is fed into the drum until it is 30 of a fine enough consistency to pass through the spaces between the bars 35 of which the wall of the drum is composed. These bars are spaced to allow passage of the milled ore through the wall of the drum, and certain 35 of the bars 35^a are of a greater width than others, to lend rigidity and strength to the structure.

Arranged around the drum is a continuous screen 36, a space 37 being defined between the screen and the outer surfaces of 40 the bars 35 and 35^a. The milled ore passed into this space through the wall of the drum, by the action of gravity, and by the whipping of the slugs 33, runs through the screen 45 and drops into the trough 9 from which it is delivered to the amalgamator.

It may here be noted that this screen is detachable and may be replaced by any other screen of selected mesh, it being my 50 purpose to use screens of various sizes of mesh, depending upon the purposes to which the mill is to be put, and the material it is, in any particular instance, to handle.

The ore which is not fine enough to pass 55 through the screen finds its way back into the drum through the traps 38. The latter are formed by placing bars 39 at the far edges of diametrically opposed openings or spaces 40, occurring between certain of the 60 bars (the term "far edge" being considered in connection with the direction in which the drum is rotating, as indicated by the arrow in Figure 1,) and by placing corresponding bars 41 on the inside of the drum, 65 the latter bars providing beveled lips 42

which direct the coarser ore, caught by the bars 39, into the interior of the drum as the traps pass the upper point of their path and start to descend. The lips also prevent the ore passing out into the space 37 through the openings or spaces 40 of the traps. 70

In order to vibrate the screen a number of spaced vibrating rings 43 are attached to the inner side of the screen and against them a plurality of plungers 44, set in certain 75 of the bars, play. These plungers have their inner ends reduced to form shoulders abutting against plates 45 fastened to the bars, in order to prevent the plungers from falling out of the bars into the drum. Some of the plungers may have their outer ends headed as at 46, the heads resting between one of the vibrating rings and a ring 47 which encircles the drum and spaces the screen therefrom. The movement of the ore, 80 as it is milled, over the inner ends of the vibrating plungers, causes these plungers to continuously move in and out, thus constantly vibrating the screen.

Although I have described the preferred embodiment of my invention, I may desire to make such changes in the construction, combination and arrangement of parts thereof as do not depart from the spirit of the invention and the scope of the appended claims. 90

I claim:—

1. A mill of the class described comprising a rotatable drum having pervious walls, a screen surrounding the drum, in spaced relation thereto, and means connected with the drum and adapted to be actuated by the movement of the material within the drum for vibrating the screen. 100

2. A mill including a rotatable drum in which ore may be milled, a screen associated with the drum, means for allowing the milled ore to pass from the drum to the screen, and means connected with the drum and operable by the movement of the material to be milled for vibrating the screen. 105

3. A mill comprising, a rotatable drum formed of longitudinally extending spaced bars, vibrating rings movably supported on the drum, a screen supported on said rings and spaced from said drum, and plungers interposed between the drum and rings in a manner to be angaged and reciprocated by the material to be milled within the drum. 115

4. A mill comprising a rotatable drum formed of longitudinally extending spaced bars, vibratory annular rings movably supported on said drum, a cylindrical screen supported on said annular rings and spaced from said spaced bars, plungers interposed between the spaced bars and said annular rings, a shaft extending longitudinally through the drum and rotatable independently thereof, and slugs flexibly mounted on said shaft and adapted to be thrown 120 125 130

outwardly and travel in a circular path adjacent the inner faces of the aforesaid spaced bars by centrifugal force.

5. In a mill of the class described, a drum having pervious inner cylindrical wall through which ore milled in the drum may pass, a cylindrical screen surrounding said

pervious wall and spaced therefrom, and return traps within the inner wall, said traps including spaced apart longitudinal 10 bars, the innermost having one side edge projecting beyond the other bar and bevelled inwardly.

HARRY LOEVEN.
